UNITED STATES PATENT OFFICE.

JOHN H. ELWARD, OF STILLWATER, MINNESOTA.

TRACTION-ENGINE.

SPECIFICATION forming part of Letters Patent No. 268,648, dated December 5, 1882.

Application filed August 24, 1881. (No model.)

To all whom it may concern:

Be it known that I, JOHN H. ELWARD, a citizen of the United States, residing at Stillwater, in the county of Washington and State 5 of Minnesota, have invented certain new and useful Improvements in Traction-Engines; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 Figure 1 is a side elevation of a traction-engine embodying my invention. Fig. 2 is a sectional view taken on line xx , Fig. 1. Fig. 3 is a plan view of the steering devices. Figs. 4, 5, 6, and 7 are detail views.

20 The brake, it will be seen, is so situated as to come in contact with the wheel at a point between the highest and the lowest points of its periphery. By this arrangement I avoid all interference with the belt or band that may 25 be used upon the wheel when thrashing or using the engine for other purposes while stationary, the legs or strands of the belt passing out of contact with the wheel at the highest and lowest points of its periphery, and I can 30 stop the motion of the band itself.

The band-wheel is mounted upon the main shaft S' , which carries also the main driving spur-wheel M . The wheel M gears and runs continuously with the secondary gear-wheel 35 M' , having upon its side a pinion, M^5 . The pinion M^5 is arranged to mesh alternately with the inner teeth and the outer teeth of a double gear wheel, $M^2 M^3$. This double geared wheel can be shifted in its position to bring either 40 the inner or the outer teeth into mesh with the pinion M^5 . In my former patent I provided for the sliding of the double geared wheel rectilineally to and from the pinion. I have, however, found the last said method in many 45 respects inferior to that which I have herein shown, and will now describe. The double geared wheel $M^2 M^3$ is loosely mounted on the shaft F . This shaft has eccentric journals F' projecting from its ends, and it will be seen 50 that if the journals $F' F'$ be revolved one-half way around they will throw the shaft F into two positions, one being the nearest to and the

other the farthest from the pinion M^5 . To thus partially rotate the journals, I employ a rack-lever, H , and pinion G , the latter being carried by the inner journal, F' . With the shaft is carried the double geared wheel $M^2 M^3$, and thus either set of teeth can be caused to engage with the pinion M^5 . When the inner set, M^2 , thus engage, the engine is moved forward. 55 When the outer set, M^3 , engage, the engine is moved backward. If the journals $F' F'$ be turned only one-quarter of a revolution, the shaft, and with it the wheel $M^2 M^3$, will be stopped in such a position that neither of the 60 sets of teeth will engage with the wheel M^5 , and therefore the connection between the engine and the traction-wheels will be broken. These latter are the relative positions in which the parts are when the engine is used for 65 thrashing, or as a stationary motor for other machinery.

Power is transmitted from the wheel $M^2 M^3$ to the traction-wheels by means of a chain, K' , and a sprocket-wheel, M^4 . This sprocket-wheel is supported outside of the wheel $M^2 M^3$, and is loose thereon. A bearing is provided for it by a circle or annulus, J , which is bolted to the outside of wheel $M^2 M^3$. With this annulus there is cast or formed a flange, J^3 , which 80 can lie upon the outside of a portion of the sprocket-wheel M^4 , and when this part $J J^3$ is fastened in place the sprocket-wheel has a secure bearing, but can be at any time perfectly loose from the wheel $M^2 M^3$. 85

The frictional engagement between the sprocket-wheel and the wheel $M^2 M^3$ is caused by cams $F^2 F^2$, a series of any suitable number of said cams being arranged around the shaft F . These cams are pivoted at J^2 to ears J' 90 projecting outwardly from flange J^3 . Each cam carries an arm, j , projecting inwardly toward the shaft F . F^3 is sliding hub, mounted upon shaft F , and the inner ends of the cam-arms $j j$ engage with this hub, and are moved 95 out and in with it. The hub is thus moved by a forked hand-lever, H^4 , pivoted to a bracket, h , on the outside of the boiler. When the hub is moved inward the cams are forced against the sprocket-wheel M^4 , crowding it tightly 100 against the wheel $M^2 M^3$, and holding it in engagement therewith until the hub is again shifted outward.

In my Patent No. 236,565 there is shown a

method of connecting the engine with the traction devices by means of a cone and a hollow cup-shaped flange carried by the gear-wheel; but having found the conical devices to be of an inferior nature under some circumstances, and also that it is often difficult to shift the gear-wheel when the parts are in motion, I have been led to devise the above-described construction and arrangement of parts.

10 It will be seen that the inner annular part carried by the chain-wheel and the opposing face of the wheel $M^2 M^3$ constitute a friction-clutch, one part of which is connected with the train or series of gear-wheels operated by the shaft, and the other part of which consists of the traction devices proper.

I am aware that friction-clutches have been heretofore used directly on the main shaft; but when so arranged they cannot be utilized 20 in conjunction with the reversing mechanism to effect the same purposes that I can accomplish by first having a series of gear-wheels or their equivalents driven by the main shaft, parts of said gears being used to reverse, and 25 then interposing a friction-clutch between the reversing mechanism and the traction-wheels. If the machine should be in motion under such circumstances that it becomes necessary to employ great force in stopping it, I can bring 30 a great braking-power into play by the devices shown. The clutch can be quickly thrown out, the gear-wheels reversed, and the clutch then brought back into engagement with the gearing either gradually or quickly. 35 If gradually, the clutch-faces will operate as a powerful friction-brake to overcome the momentum of the machine upon the ground-wheels and bring said wheels speedily to a stop, and after being thus utilized as a brake 40 the clutch-faces may be brought into complete engagement and the reverse motion of the gearing be communicated to the traction-wheels in the direction opposite to that in which they were moving just before the friction-faces were used as a brake.

45 The outer journal, F' , of shaft F is supported by means of braces $B B'$, secured to the outside of the boiler. The shaft is held from moving endwise inwardly by reason of the inner 50 end abutting against the inner supporting-bracket, B^3 , and from moving outwardly by pinion G , which is tightly keyed to the inner journal, F' , inside of the bracket B^3 . The bracket-support $B B'$ is an important feature of this 55 construction over those which have been heretofore used, as by this means a firm support is provided at the outer end of the shaft F , the shafts corresponding thereto heretofore having been provided with bearings only at 60 the inner end. The construction and arrangement herein shown prevent any shaking or loosening of the parts and hold them firmly in their proper relations.

65 The devices for steering the engine are constructed and operated as follows: $R^2 R^2$ represent the front or truck wheels, and R their axle, connected to the engine by a vertical

pivot, in the usual manner. W is a drum connected to the under side of the boiler between the rear and the front wheels. Its axis is situated vertically, and the drum is supported by means of a strong bracket, W' . At its upper end it carries a bevel-wheel, A . H' is an inclined shaft, extending to the operator's platform, and provided with a bevel-wheel, A' . 70 By means of a counter-shaft, U , and bevel-wheels U' and U^2 a connection is made between the bevel-wheel A' and the wheel A . L' represents a chain or rope wound around the drum W , and having its end attached at 75 or near the ends of the front axle, R . By these devices the operator can readily throw the truck frame and wheels into any of the positions shown in Fig. 3.

What I claim is—

1. In a traction-engine, the combination of 85 the traction-wheels, the main engine-shaft, the train or series of gearing-wheels driven by said shaft, the mechanism separable from said train or series of wheels for driving the traction-wheels, and the friction-clutch interposed between said traction driving mechanism, and the train of wheels operated by the shaft, as and for the purposes set forth.

2. In a traction-engine, the combination of 95 the traction-wheels, the main engine-shaft, the train or series of gear-wheels driven by said shaft, the means for reversing the direction of the last wheel of the train or series, and the friction-clutch between the mechanism for driving the traction-wheels, and the reversible wheel, substantially as and for the purposes 100 set forth.

3. In a traction-engine, the combination of 105 the traction-wheels, the engine-shaft, the train or series of gear-wheels driven by said shaft, the chain-wheel M^4 for driving the traction-wheels, the means for reversing said chain-wheel, and the friction-clutch interposed between the reversing mechanism and the chain-wheel, substantially as and for the purposes 110 set forth.

4. The combination, with the chain-wheel M^4 , the wheel M^5 , and the intermediate mechanism for driving the chain-wheel, of the shaft 115 F , situated centrally within said chain-wheel, the journals F' , attached to said shaft eccentrically, and the shifting mechanism for rolling the shaft F on said eccentric journals, substantially as set forth.

5. The combination, in a traction-engine, with the chain K' and the shifting gear-wheel $M^2 M^3$, of the sprocket-wheel M^4 , loosely supported by said wheel $M^2 M^3$, and mechanism, substantially such as described, for forcing the sprocket-wheel into frictional engagement 125 with the said wheel $M^2 M^3$, as set forth.

In testimony whereof I affix my signature in presence of two witnesses.

JOHN H. ELWARD.
